Attorney

UNITED STATES PATENT OFFICE

HENRY MILTON GRILLS, OF TORONTO, ONTARIO, CANADA

GRENADE SUPPORT FOR FIRE EXTINGUISHERS

Application filed June 11, 1928. Serial No. 284,414.

My invention relates to a support for releasably holding a fire extinguishing grenade and is characterized by a hanger, which can be attached to a wall or other structure, 5 a bracket fusibly connected to the hanger, and a grenade holder secured to the bracket.

For an understanding of the invention reference is to be had to the following description and to the accompanying drawings, in 10 which:

Fig. 1 is a front elevation of the support showing the grenade in dotted lines,

Fig. 2 is a horizontal section on the line A—A, Fig. 1,

Fig. 3 is a vertical section on the line B—B, 15 Fig. 1.

Like characters of reference refer to like parts throughout the specification and drawings.

20 The container or grenade 1, which may take the form of a fragile bottle or flask of ample storage capacity, is filled with fire extinguishing fluid and held in a suspended position by a support which may be permanently or re- 25 movably attached to a wall or other suitable structure.

In the construction hereinafter described the support comprises:—a hanger 2, which takes the form of a flat plate provided with 30 flanged edges 3, and has an aperture 4 at or near the top intermediate its lateral sides; a bracket 5, of corresponding shape and dimensions to that part of the hanger which it contacts, provided with flanges 6 at its lateral 35 and bottom edges for engaging the corresponding flanged edges of the hanger and preventing the upward and sidewise movements of the bracket, independently of the hanger; and a grenade holder 7 secured to the bracket 40 et 5.

The grenade holder 7 may consist of any suitable structure capable of holding the grenade, and in the preferred form consists of an infusible wire band or strap, shaped to 45 conform to, and of sufficient strength and rigidity to support the weight of, the container or grenade. The two ends of this band or strap are bent back upon the body as at 8^a and then bent at right angles to its plane to 50 form two arms 8, each of which is entered in a

pair of vertically disposed and separated sockets 9, 9^a which may be integral with or pressed from the body of the bracket 5 or may be separate from and secured to it by any well known mechanical expedient. 55

The bracket 5 is formed with an aperture 10 through which is entered a fusible fastener 11 for uniting the bracket to the hanger. This fusible fastener consists of a metallic alloy which melts at a relatively low temperature, usually but slightly above maximum atmospheric temperature, to permit of the separation of the bracket from the hanger, but otherwise securely fastens the bracket and hanger together and maintains the assembly 60 of the component parts of the support. 65

Any type of a fragile container or grenade may be employed for the fire extinguishing fluid and in the construction shown it is substantially ovoidal with the larger diameter of 70 the ovate above the band or strap for the latter to support it from below.

In the use of the apparatus the support is attached at an elevated position, to a wall or other structure. When the temperature of 75 the premises reaches the fusion point of the metallic alloy, the fastener melts and permits the bracket and hanger to separate and the container or grenade to fall and break for liberating its contents. 80

Having thus fully described my invention, what I claim as new and desire to secure by Letters Patent is:

1. A grenade support comprising a flat hanger plate for attachment to a supporting 85 structure, a bracket contacting part of the hanger plate, a fusible fastener entered through the bracket and hanger plate for securing them together under normal temperature conditions and permitting them to separate when the temperature exceeds a predetermined degree, and an infusible grenade holder connected to the bracket for embracing the grenade and supporting it from below. 90

2. A grenade support comprising a flat hanger plate having flanged edges, a bracket 95 contacting part of the hanger plate and of corresponding shape and dimensions to that part of the hanger plate which it contacts, a fusible fastener entered through the bracket 100

and hanger plate for securing them together under normal temperature conditions and permitting them to separate when the temperature exceeds a predetermined degree,

- 5 flanges at the lateral sides of the bracket engaging the corresponding flanged edges of the hanger plate for preventing the sidewise movement of the bracket independently of the hanger plate and relieving the fusible fastener of lateral strain resulting from such sidewise movement, and an infusible grenade holder secured to the bracket for embracing the grenade and supporting it from below.
- 10 3. A grenade holder comprising a flat hanger plate provided with flanged edges, a bracket contacting part of the hanger plate and of corresponding shape and dimensions to that part of the hanger plate which it contacts, a fusible fastener entered through the

- 20 bracket and hanger plate for securing them together under normal temperature conditions and permitting them to separate when the temperature exceeds a predetermined degree, flanges at the lateral sides of the bracket 25 engaging the corresponding flanged edges of the hanger plate for preventing the sidewise movement of the bracket independently of the hanger plate and relieving the fusible fastener of lateral strains, resulting from such sidewise movements, and a grenade holder secured to the bracket consisting of an infusible strap shaped to conform to the grenade for embracing it and supporting it from below.
- 30 4. A grenade holder comprising a flat hanger plate provided with flanged edges a bracket contacting part of the hanger plate and of corresponding shape and dimensions to that part of the hanger plate which it contacts, a fusible fastener entered through the bracket and hanger plate for securing them together under normal temperature conditions and permitting them to separate when the temperature exceeds a predetermined degree, flanges at the lateral sides of the bracket 35 engaging the corresponding flanged edges of the hanger plate for preventing the sidewise movement of the bracket independently of the hanger plate and relieving the fusible fastener of lateral strains, resulting from such sidewise movements, a grenade holder secured to the bracket consisting of an infusible strap shaped to conform to the grenade for embracing it and supporting it from below having two arms at right angles to its plane, and vertically disposed sockets for the bracket in which the arms are entered.

Dated at the city of Toronto, in the county of York and Province of Ontario, Dominion of Canada, the seventh day of May, 1928.

HENRY MILTON GRILLS.
